D. N. ROSS

PLATE ATTACHING MEANS

Filed May 9, 1927

Fig. 5.

INVENTOR,
David N. Ross.

By Minturn & Minturn,
Attorneys.

UNITED STATES PATENT OFFICE.

DAVID N. ROSS, OF INDIANAPOLIS, INDIANA, ASSIGNOR TO DAVID N. ROSS, INCORPORATED, OF INDIANAPOLIS, INDIANA, A CORPORATION OF INDIANA.

PLATE-ATTACHING MEANS.

Application filed May 9, 1927. Serial No. 189,779.

Most owners of automobiles are members of some automobile club or association, or carry insurance on their cars. As evidence of such facts, the owners receive a plate indicative of the club, association, or insurance company, to be attached to the front end of the car.

Heretofore, such plates have been provided with flexible wires either soldered or brazed to the back of the plate or passed through the plates with retaining heads, whereby the plates may be positioned and secured on the front of the radiator cores of the cars. Other means, such as studs permanently fixed to the plates or passed through the plates have been employed. All of such means, however, have become useless if not entirely inoperative through the advent of the radiator shutter which covers the front side of the radiator core and therefore prevents display of such plates thereon. It has, therefore, become necessary to attach the plates to some other member of the car, and the most satisfactory member is the usual transverse brace or tie rod between the fenders or head lamps or a front bumper bar. As such braces, rods, and bars vary considerably in cross-sectional shape and size, the old means of wires or studs being spaced apart at a fixed distance can not be employed to meet such variations. Moreover, studs or wires permanently fixed to the plates interfere greatly in shipping the plates in quantity.

This invention overcomes all these difficulties by providing the means for attaching the plates that is universally adapted to the entire range of sizes and shapes of braces, rods, and bars encountered in automobile practice, and is described in reference to the accompanying drawing, in which—

Fig. 1, is a side elevation of the attaching means supporting a plate in relation to a section of small diameter tubing;

Fig. 2, a rear elevation of the attaching means;

Fig. 3, an end elevation of the attaching means;

Fig. 4, a section on the line 4—4 of Fig. 3; and

Fig. 5, a side elevation of the attaching means supporting a plate in relation to a large, bar square in cross section.

Like characters of reference indicate like

parts throughout the several views of the drawing.

To the back of the plate 10 to be supported or attached is brazed, welded, or soldered (the method of affixing being immaterial) 60 a bar 11, so that the bar becomes firmly and permanently secured to the plate 10. The bar 11 has a central inverted U-section portion to provide the surface 12 spaced above the plate 10.

The surface 12 has a central opening 13 cut through, and extending centrally of the surface 12 each way from the opening 13 are the slots 14 and 15, the slots terminating before reaching the outer ends of the surface 12. A square-headed bolt 16 is entered by its head 17 through the opening 13 to be engaged by the slot 14, the head 17 being thereby retained from the under side of the surface 12. Similarly, a bolt 18 is entered 75 in the opening 13 and moved into the other slot 15 to have its head 19 retained under the surface 12.

The plate 10 is then presented to the supporting rod 20 as in Fig. 1, or any other available support such as the bar 21 in Fig. 5, to have the bar 11 transversely contact the rod 20 by the surface 12 with the bolt 16 passing to one side of the rod 20 and the bolt 18 to the other side. The two bolts 16 85 and 18 are moved in the slots 14 and 15 toward the rod 20 therebetween, and a bar 22, having the rod contacting feet 23 and 24 with the outwardly extended central inverted U-section 25 therebetween, is presented 90 behind the rod 20 to permit the bolts 16 and 18 to extend therethrough.

The section 25 is perforated with a plurality of closely spaced holes 26 through which the bolts 16 and 18 may selectively be passed 95 as determined by the diameter or width of the rod 20. A lock washer 27 and wing nut 28 is used on each bolt 16 and 18 to bear against the surface 25 whereby the two feet 23 and 24 press against the rod 20 to grip 100 it firmly against and on the surface 12, which in effect is a grip on the rod between the two points from the rear side and the single point on the forward side.

As above indicated, the bolts 16 and 18 may be spaced apart in the slots 14 and 15 to accommodate various sizes of supporting rods and the like. Also, it is to be noted, that the bolts 16 and 18 are of sufficient length to accommodate the varying size of 110

supports. While the plate 10 here shown is circular in shape, such shape is immaterial to the invention as the bar 11 may be attached to the back of any other shaped plate.

I claim:

1. Means for attaching a plate to a support comprising a bar secured to the plate, a surface extended from the bar to leave a space from the plate thereunder, said surface having a central opening therethrough and a slot extending from the opening toward each end of the extended surface, bolts entered through said opening into said slots to have their heads retained thereunder, a second bar having a plurality of holes to selectively receive said bolts therethrough, said support being between said two bars, and nuts on said bolts.
2. Means for attaching a plate to a support comprising a bar of substantial length secured to the plate, an inverted U-section centrally extended from the bar throughout its length, said U-section having a central open-

ing therethrough, and a longitudinal slot 21 from opposite sides of the opening in the U-section toward each end, a second bar, a central longitudinal inverted U-section extended from said bar in the same relation as that of said first bar, said U-section of the second bar having a plurality of holes therethrough, bolts guided in said slots, heads on said bolts retained under said slots, said bolts being selectively passed through said U-section holes, and nuts on said bolts.

3. Means for attaching a plate to a support comprising a bar secured to the plate, a longitudinal raised section of the bar having a slot substantially throughout its length and an enlarged opening into said slot, bolts 40 having heads adapted to enter said opening and be passed under said slot, a second bar engaged by said bolts, said support being between said two bars, and said second bar having two lines of contact on said support 45 spaced apart one from the other.

In testimony whereof I affix my signature.
DAVID N. ROSS.
